UNITED STATES PATENT OFFICE.

HATTIE ILIGAN, OF EAST ELMHURST, NEW YORK.

WINDOW SHADE.

Application filed December 8, 1925. Serial No. 74,104.

This invention relates to roller window shades and particularly to devices of this class provided with means whereby air may be passed therethrough for ventilating purposes; and the object of the invention is to provide a shade of the class described with one or more openwork portions or apertures through which air is adapted to pass when the shade is in extended position; a further object being to provide means for covering or ornamenting the openwork or apertured portion of the shade, said means being in the form of a mesh fabric or body such as curtaining material; a still further object being to provide a shade of the class described, a predetermined portion of which may be fashioned or constructed to form a window curtain for covering a part of the window area; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is an inside view of a window showing one form of my improved shade mounted therein and indicating the method of its use.

Fig. 2 is a detail view of a part of a shade showing a modified form of construction.

Fig. 3 is a view similar to Fig. 2 but showing another modification; and,

Fig. 4 is a view similar to Fig. 1 but showing a modified form of shade.

The distinctive feature of my invention consists in providing a ventilating section or area in or as part of a window shade, and particularly a shade of the roller type whereby air for ventilating purposes, when one or both of the sashes of the window are open, may pass through the shade and prevent the flapping of the shade when subject to heavy winds or draughts of air and also to the provision of means in the form of an openwork body for covering the opening to obstruct vision through the shade. In Fig. 1 of the drawing, I have shown at 5 one form of shade I may employ and which is mounted upon the usual type of shade roller, detachably supported in the upper end portion of

the window frame 6 in which the sashes 7 are movably mounted. The shade 5 may be of the usual or any preferred form and construction and the free end of which is provided with the usual stiffening means and pull cord 8. In the body of the shade 5 is formed an elongated and narrow opening 9 which extends transversely of the shade, and said opening is covered by a body 10 of openwork material, preferably curtaining material which is also preferably ornamented to give a neat and attractive appearance to the complete shade.

The opening 9 may be arranged in the shade 5 at any desired point, that is to say, adjacent the upper or lower end thereof or centrally of the shade. In the construction shown, the opening is arranged adjacent the upper end to register with the opening of the top sash of the window when the shade is withdrawn from the roller to cover approximately two thirds of the window opening, but this use is merely illustrative, and it may be more desirable to have the opening 9 arranged at the top of the window sash when the shade is fully extended and covers the entire window opening or adjacent the lower end of the shade when in such position, in which latter use, the lower sash of the window will be raised from the bottom.

With a construction as shown in Fig. 1 of the drawing, it will be apparent that by bringing the apertured or cut-out portion 9 of the shade in position to register with the opening in the window formed by raising the lower sash, or lowering the upper sash, the air is permitted to pass freely through the shade without causing the flapping thereof as is commonly experienced. It will also be understood that by providing a comparatively fine mesh, vision through the aperture or opening 9 is prevented and said body may also serve as a screening in the manner of other ventilating screens now in common use.

In Fig. 4 of the drawing, I have shown a modification of the structure shown in Fig. 1 wherein the shade 5^a is provided adjacent its free end with a large rectangular aperture or opening 11, preferably of such dimensions as to register with the panels of one of the sashes 7, for example the lower sash, and this opening or aperture is closed or covered by a body of curtaining material 12 which forms when in use, a curtain for the lower portion of the window. In other

words, the structure shown in Fig. 4 produces a combination shade and curtain construction mounted upon a shade roller and movable collectively into different positions. The body of curtaining or other openwork material 12 permits of the passage of air therethrough whereby the ventilating features of the shade are maintained. It will be understood that this body 10 may be positioned at any point in a window frame that may be desired.

In Fig. 2 of the drawing, I have shown another method of carrying my invention into effect which consists in providing the shade 5^b with a plurality of transversely spaced apertures or openings 13, which openings may be positioned on the shade in such manner as to register with the upper, lower or any other portion or section of a window frame whereby ventilating air passed through the window when one of the sashes are in open position may be directed through the apertures 13.

In Fig. 3 of the drawing, I have shown another modification in which a window shade 5^c is provided with a plurality of spaced L-shaped slits or cuts 14 to form spaced openings 15 which may be closed or partially closed by flaps 16 formed from the material of the shade and in the cutting or slitting 14. In other words, instead of removing the fabric of the shade in cutting apertures such as 13 in Fig. 2 of the drawing, the shade is merely slitted or cut to form openings which may be closed or partially closed by the flaps resulting. It is to be noted that the free edges of the flaps 16 are directed away from the roller of the shade to facilitate the easy and proper rolling and unrolling of the shade on said roller, and to prevent creasing of said flaps. It will also be understood that the shade 40 may be suitably constructed where the cuts

or slits 14 are arranged therein to prevent tearing or ravelling.

It will be understood that while I have shown certain details of construction for carrying my invention into effect, that I am not necessarily limited to these details, and various changes therein and modifications 50 thereof, may be made within the scope of the appended claims without departing from the spirit of my invention or sacrificing its advantages.

Having fully described my invention, 55 what I claim as new and desire to secure by Letters Patent, is:—

1. A window shade having a plurality of ventilating passages therein, and means integral with said shade for forming partial 60 closures for said passages.

2. A shade of the class described provided with a plurality of substantially L-shaped cuts whereby portions of the shade are severed to form substantially triangular 65 flap portions, and corresponding ventilating openings controlled by said flap portions.

3. A roller shade provided with a plurality of spaced openings formed by cutting the shade by vertical and horizontal slits, 70 the horizontal slits joining the vertical slits and being at the lower end of the vertical slits with relation to the roller of the shade, and the flap portions formed by slitting the shade controlling the openings therein. 75

4. A roller shade of the class described provided with a plurality of transversely spaced elongated apertures, said apertures extending longitudinally of the shade, and flaps for the separate apertures, and cooperating therewith. 80

In testimony that I claim the foregoing as my invention I have signed my name this 4th day of Dec. 1925.

HATTIE ILIGAN.
